TRAIN ORDER HOLDER

Vernon H. Campbell, Polo, Mo., assignor of one-half to O. J. Adams, Kingston, Mo.

Application October 19, 1943, Serial No. 506,885

2 Claims. (Cl. 258—2)

The present invention relates to new and useful improvements in train order holders, and has for its primary object to provide, in a manner as hereinafter set forth, a device of this character which is adapted to accommodate a plurality of orders, one to be brought automatically into position for delivery when the other is removed.

Another very important object of the invention is to provide a multiple train order holder of the character described which may be readily adjusted vertically as desired.

Still another important object of the invention is to provide an order holder of the aforementioned character which is adapted to deliver orders to trains passing thereby in opposite directions.

Other objects of the invention are to provide an adjustable, multiple train order holder which will be comparatively simple in construction, strong, durable, highly efficient and reliable in use, compact, and which may be manufactured and installed at low cost.

All of the foregoing, and still further objects and advantages of the invention will become apparent from a study of the following specification, taken in connection with the accompanying drawings wherein like characters of reference designate corresponding parts throughout the several views, and wherein:

Figure 1 is an elevational view of a train order holder constructed in accordance with the present invention.

Figure 2 is a fragmentary view in vertical section through the lower portion of the device, taken substantially on the line 2—2 of Figure 1.

Figure 3 is an elevational view of an intermediate portion of the device, showing one of the vertically adjustable fork-retaining units.

Figure 4 is a view in horizontal section through the telescopically adjustable standard, showing one of the fork-receiving units in top plan.

Figure 5 is a fragmentary view in horizontal section, taken substantially on the line 5—5 of Figure 3.

Figure 6 is a detail view of the outer end portion of one of the fork arms.

Figure 7 is a detail view of one of the strings through the medium of which the orders are mounted on the forks.

Referring now to the drawings in detail, it will be seen that the embodiment of the invention which has been illustrated comprises a vertically adjustable, tubular metallic standard or pole which is designated generally by reference numeral 1. The standard 1 includes telescopic

lower, intermediate and upper sections 2, 3 and 4, respectively, said section 2 being embedded in the ground, as at 5, to the desired depth. Collars 6 are provided on the upper end portions of the sections 2 and 3. Clamping screws 7 are threaded through the collars 6 and the upper end portions of the sections 2 and 3 for releasably securing the standard 1 in adjusted position.

Mounted at spaced points on the upper section 4 of the standard 1 are vertically adjustable right and left hand order-retaining units which are designated generally by reference numeral 8. The units 8 are for delivering orders to trains traveling in opposite directions. As the units 8 are similar in construction and operation, a detailed description of one will suffice for both.

Each unit 8 includes a metallic sleeve 9 which is adjustable vertically on the upper section 4 of the standard 1. A screw 10 releasably secures the sleeve 9 in adjusted position. Projecting horizontally from the sleeve 9 is a shaft 11. A block 12 is journaled on the shaft 11 between cotter pins 13 which retain said block in position on said shaft. Tubes 14 are fixed on the block 12 and project at right angles relative to each other therefrom. The tubes 14 are provided with bayonet slots 15 in their outer end portions.

The tubes 14 are for the reception of the stems 16 of forks 17 for removably mounting said forks on the unit 8. Guides in the form of resilient clips 18 are mounted on the outer ends of the arms 19 of the forks 17. The guides 18 slidably retain on the forks 17 strings 20 to which the orders to be delivered, as at 21, are tied. Pins 22 on the stems 16 of the forks 17 are engageable in the bayonet slots 15 for anchoring said forks in the tubes 14. Coil springs 24 in the tubes 14 are engageable with the inner ends of the stems 16 for seating the pins 22 in the inner end portions of the bayonet slots 15.

Also fixed on the sleeve 9 is an arm 25 which parallels the shaft 11. A dog 26 is pivotally mounted on the free end portion of the arm 25 and is engageable with the lower tube 14 for releasably supporting the corresponding fork 17 in delivery or horizontal position. Rising from the arm 25 is a post 27 having mounted on its upper end portion a guide 28. The guide 28 slidably accommodates the lower string 20 which is looped over the upper end portion of the dog 26 for swinging said dog to inoperative position. A resilient clip 29 on the upper end portion of the dog 26 retains the string 20 thereon.

Also mounted on the sleeve 9 and projecting horizontally therefrom are upper and lower

stops 38 and 31, respectively, for engagement by the tubes 14. The lower stop 31 includes, on its outer end, a resilient clip 32 for retaining the lower tube 14 when it drops into engagement with said stop 31.

It is thought that the operation of the device will be readily apparent from a consideration of the foregoing. Briefly, the forks 17, with the orders 21 mounted thereon, are mounted in the tubes 14. The tubes 14 are then swung in a vertical plane on the shaft 11 for engaging one of said tubes with the stop 38 and for permitting the dog 26 to engage beneath the other of said tubes. Thus, the fork 17 from which the first delivery is to be made is supported in a horizontally projecting position on the standard 1 and the other fork 17 is retained in a vertical position adjacent said standard. The lower strings 28 are then inserted through the guides 28 and looped over the upper end portions of the dogs 26 where they are retained by the clips 29. The device is now ready for operation. When the strings 28 on one of the lower forks 17 is pulled as the delivery is being made, said string, slipping through its respective guide 28, disengages the dog 26 from beneath the lower tube 14. Thus, the upper fork 17 is permitted to swing downwardly to a horizontal position and the device is ready for the next delivery.

It is believed that the many advantages of a train order holder constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A train order delivery device comprising a vertical standard, a shaft projecting laterally from the standard, diverging tubular arms journaled on said shaft, order-holding forks having stems removably telescoped in said tubular arms, easily removable flexible order-carrying members carried by said forks, horizontal stops pro-

jecting from said standard, one of said stops limiting upward movement of one arm to a substantially vertical inoperative position, the other stop limiting downward movement of the other arm to a substantially vertical inoperative position, a vertically swinging dog mounted on the standard and engageable under said other arm to support it in a substantially horizontal operative position with the one arm substantially vertical, and a guide carried by said standard and located between the latter and the dog, the flexible order-carrying member of the fork carried by said other arm being threaded through said guide and engaged with the dog for releasing the latter and allowing the arms to lower to bring the one arm into a substantially horizontal operative position when the last-named flexible order-carrying member is removed from its fork.

2. A train order delivery device comprising a vertical standard, a sleeve vertically adjustable on the standard, a shaft projecting laterally from the sleeve, diverging tubular arms journaled on said shaft, order-holding forks having stems removably telescoped in said tubular arms, easily removable flexible order-carrying members carried by said forks, horizontal stops projecting from said sleeve, one of said stops limiting upward movement of one arm to a substantially vertical inoperative position, the other stop limiting downward movement of the other arm to a substantially vertical inoperative position, a vertically swinging dog mounted on the sleeve and engageable under said other arm to support it in a substantially horizontal position with the one arm substantially vertical, and a guide carried by said sleeve and located between the latter and the dog, the flexible order-carrying member of the fork carried by said other arm being threaded through said guide and engaged with the dog for releasing the latter and allowing the arms to lower to bring the one arm into a substantially horizontal operative position when the last-named flexible order-carrying member is removed from its fork.
